UNITED STATES PATENT OFFICE.

JOHAN AUGUST WIBORGH, OF STOCKHOLM, SWEDEN.

DROP-TARGET.

No. 877,622.

Specification of Letters Patent.

Patented Jan. 28, 1908.

Application filed January 25, 1907. Serial No. 353,986.

To all whom it may concern:

Be it known that I, JOHAN AUGUST WIBORGH, a subject of the King of Sweden, and resident of Stockholm, Sweden, have invented new and useful Improvements in Drop-Targets, of which the following is a specification, reference being had to the drawing accompanying and forming a part hereof.

10 This invention relates to drop targets.

Targets arranged to drop when hit by a shot are known in various forms generally based on the principle that the shot hitting the target imparts to the latter, by impact on the same, a movement sufficient to release a detent normally retaining the target in operative position. In firing at such targets with the modern rifles of small caliber it has, however, been found that the targets 20 are only exceptionally dropped by hits, due to the fact that the movement which a shot from a modern rifle is capable of imparting to the target is, in most cases, too small to release the detent. Moreover, the 25 said targets have the drawback that they will be dropped by slight puffs of wind, which obviously entails inconveniences.

The object of the invention is to obviate the said inconveniences and provide a drop 30 target which is safe and reliable in action.

The invention consists, chiefly, in that the target proper is made hollow and actuated by a movable member, such as a diaphragm, a piston, or the like, operated by high or low 35 pressure (vacuum), respectively, prevailing within the target proper, said movable member, being connected with a trap, or detent, normally retaining the target proper in operative position, whereas, when the high 40 or low pressure, respectively, within the target proper is destroyed by a shot passing therethrough, the trap, or detent, is released and the target proper drops under the influence of gravity or other power, such as 45 that exerted by a spring, or the like.

In the drawing, Figure 1 is a vertical section and partial elevation of a drop target embodying my invention. Fig. 2 is a horizontal section of the same on line x—x of 50 Fig. 1.

Referring to the drawing, the figure representation or target proper 1, which may be made of, for instance, paper pulp or other suitable material, is shown fastened by 55 means of suitable adhesive into a frame 2 situated on a tube 3, said tube being mount-

ed in bearings 4 on a foot plate 5 in such a manner as to be able to turn about its longitudinal axis. Situated in the bottom 6 of the figure representation 1 is an opening 60 (or more) coinciding with a corresponding opening 7 (or openings) in the wall of the tube 3 by which the cavity of the figure representation communicates with the interior of the tube 3. Placed in the said tube, 65 which is air-tightly closed at one end, is a piston 8 adapted to slide within the tube, without allowing air to pass between the piston and the inner wall of the said tube, said piston being connected to a rod 10 extending through a cover 9 from within the tube 3.

Situated at the outer end of the rod 10 is a head or cross piece 11, or the like, adapted to be engaged by a catch 12, or the like, attached to the foot plate, by which the piston 8 can be releasably held in position against the action of a spring 13 interposed between the cover 9 and the piston 8 while a part of the target proper penetrated by a bullet is 80 repaired in the ordinary manner by attaching pieces of paper, or the like, to the target proper by means of a suitable adhesive, such as glue, or paste. In the embodiment illustrated the figure representation or target 85 proper 1 is held in upright position by an arm 14 projecting from the tube 3, said arm being engaged by a rod 15 adapted to be moved in its longitudinal direction. The rod 15 is pivotally attached to the one arm 90 of a double-armed lever 17 mounted on a pivot 16, the other arm of said lever being actuated by a pin or lug 18 projecting from the rod 10, when the piston 8 moves toward the closed end of the tube 3 in the manner to 95 be described.

The described arrangement is used and works in the following manner. Supposing the parts to take up the positions illustrated and the catch 12 to be withdrawn from engagement with the head 11 of the rod 10, the piston 8 moves inwardly under the action of the spring 13, thereby compressing the air within the tube and the target proper. When the pressure within the said parts balances 100 the pressure exerted by the spring 13, the piston 8 ceases to move, the arrangement being such that the pin 18 does not actuate the lever 17 during this primary movement of the piston. The target proper thus remains 105 locked by the rod 15 in its normal position of rest and is now ready for use. If a bullet, or

missile, penetrates the target proper, the air pressure within the latter is destroyed, and the piston moves further inwardly under the action of the spring 13, whereby the pin 18 turns the lever 17 so that the rod 15 is thrown out of engagement with the arm 14. The target proper 1, which in its normal position of rest has its center of gravity somewhat at the side of the longitudinal axis of the tube, then immediately drops. For dropping the target a spring or springs might also be used, if desired.

The embodiment illustrated can obviously be modified in several ways without departing from the spirit and scope of my invention. This is especially the case as far as the piston is concerned, which may be replaced by another movable member, such as a diaphragm, or the like. The air pressure within the target proper may be higher or lower than that of the atmosphere, as also is the case of a vacuum existing within the target the piston, or the diaphragm, or the like, may be caused to move, when the target is hit and the air enters the interior thereof through the holes made by the shot.

Having now described my invention, what I claim as new and desire to secure by Letters Patent is:—

30 1. In a drop target, the combination of a hollow, air-tight, penetrable figure representation, in the interior of which, normally, a pressure is prevailing differing from that of the atmosphere, a detent adapted to engage 35 the figure representation to normally prevent it from dropping, and means, controlled by variation of pressure within the figure representation, for releasing the detent, when the figure representation is penetrated by a hit, substantially as and for the purpose set forth.

40 2. In a drop target, the combination of a hollow, air-tight, penetrable figure representation in the interior of which, normally, a pressure is prevailing differing from that of the atmosphere, a cylinder communicating with the interior of the said figure representation, a spring-actuated member mounted within the said cylinder in such a manner as 45 to move, when the pressure within the figure representation is changed by a shot penetrating the same, a detent adapted to engage the figure representation and, thereby, keep the latter in its normal position of rest, 50 and connections between the piston and the detent for releasing the figure representation, when the piston is moved, substantially as 55 and for the purpose set forth.

60 3. In a drop target, the combination of a cylinder forming an extended tube, bearings for the said cylinder, a hollow, air-tight penetrable figure representation attached to the said cylinder and communicating with the interior thereof, means for creating with- 65 in the hollow figure representation and the

cylinder a pressure differing from that of the atmosphere, a member mounted within the cylinder in such a manner as to move, when the pressure within the figure representation and the part of the cylinder communicating therewith is changed, a detent adapted to engage the figure representation and, thereby, normally prevent the latter from dropping, and connections between the piston and the detent for releasing the figure representation, when the latter is penetrated by a hit, substantially as and for the purpose set forth.

4. In a drop target, the combination of a cylinder forming an extended tube, bearings for the same, a frame projecting from the wall of the cylinder, a hollow, air-tight, penetrable figure representation inserted into the said frame and communicating with the interior of the cylinder, means for creating within the hollow figure representation and the cylinder a pressure differing from that of the atmosphere, a member mounted within the cylinder in such a manner as to move, when the pressure within the figure representation and the part of the cylinder communicating therewith is changed, a detent adapted to engage the figure representation and, thereby, normally prevent the latter from dropping, and connections between the piston and the detent for releasing the figure representation, when the latter is penetrated by a hit, substantially as and for the purpose set forth.

5. In a drop target, the combination of a cylinder forming an extended tube, bearings for the same, a frame projecting from the wall of the cylinder, a hollow, air-tight, penetrable figure representation inserted into the said frame and fastened thereto by a suitable adhesive, said figure representation communicating through openings with the interior of the cylinder, means for creating within the hollow figure representation and the cylinder a pressure differing from that of the atmosphere, a member mounted within the cylinder in such a manner as to move, when the pressure within the figure representation and the part of the cylinder communicating therewith is changed, a detent adapted to engage the figure representation and, thereby, normally prevent the latter from dropping, and connections between the piston and the detent for releasing the figure representation, when the latter is penetrated by a hit, substantially as and for the purpose set forth.

6. In a drop target, the combination of a cylinder forming an extended tube, bearings for the same, a frame projecting from the wall of the cylinder, a hollow, air-tight, penetrable figure representation inserted into the said frame and communicating with the interior of the cylinder, a member mounted within the cylinder in such a manner as to

move, when the pressure within the figure representation and the part of the cylinder communicating therewith is changed, a catch for the piston to keep the same in an 5 inoperative position during repair of the figure representation, means for creating within the hollow figure representation and the part of the cylinder communicating therewith a pressure differing from that of the atmosphere, a detent adapted to engage the 10 figure representation and, thereby, normally prevent the latter from dropping, and con-

nnections between the piston and the detent for releasing the figure representation, when the latter is penetrated by a hit, substantially as and for the purpose set forth. 15

In testimony whereof I have signed my name to this specification in the presence of two subscribing witnesses.
